UNITED STATES PATENT OFFICE.

WILLIAM NAGLER, OF CHICAGO, ILLINOIS, ASSIGNOR TO J. H. McNAMARA TRUNK WORKS, OF CHICAGO, ILLINOIS, A CORPORATION OF ILLINOIS.

WARDROBE-TRUNK.

1,116,610.

Specification of Letters Patent. Patented Nov. 10, 1914.

Application filed July 10, 1913. Serial No. 778,233.

To all whom it may concern:

Be it known that I, WILLIAM NAGLER, a citizen of the United States of America, and a resident of Chicago, in the county of Cook, State of Illinois, have invented certain new and useful Improvements in Wardrobe-Trunks, of which the following is a specification.

This invention relates to that type of 10 wardrobe trunks in which a series of sliding clothes-hangers are disposed at one end of the trunk body, so that when said trunk body is up-ended the clothes supported by said hangers are accessible for ready removal and replacement. And the present 15 improvement has for its object to provide a simple and effective combination and arrangement of parts whereby the clothing is compressed and confined in place, when so suspended, and with which the clothing is 20 covered and protected from dust, etc., in a very effective manner, all as will hereinafter more fully appear.

In the accompanying drawings:—Figure 25 1, is a perspective view of a trunk embodying the present invention, the trunk being shown open and up-ended, and with portions broken away. Fig. 2, is a longitudinal section of the body portion of the trunk. 30 Fig. 3, is a detail section of the same, on line x—x, Fig. 2. Fig. 4, is a detail perspective view illustrating the curtains of the present improvement detached from the body of the trunk. Fig. 5, is a detached 35 perspective view of the fixed member of the track upon which the usual series of clothes hangers are mounted.

Similar numerals of reference indicate like parts in the several views.

40 Referring to the drawings, 1 represents the main portion or body of the trunk, comprising a bottom, fixed side-walls, one fixed end-wall and one hinged end wall 2, as shown.

45 3 is the cover section hinged to the aforesaid main body 1, as usual in the present type of wardrobe trunks.

4 50 4 is the hanger track, disposed adjacent to the hinged end wall 2 of the trunk body 1 and adapted to support in an adjustable manner the usual series of clothes-hangers by which the garments are suspended within the trunk body. Said hanger track is preferably of the telescopic type shown, and 55 comprising a fixed plate member of the U

form shown, and a sliding U shape member 5 having sliding adjustment in tubular guides on the fixed plate member aforesaid, as shown more particularly in Figs. 1 and 5. In the present improvement the aforesaid U shape plate member is additionally utilized in a very effective manner, as a means for securing in place the hereinafter described curtains of the present improvement.

6 60 is the main curtain attached to the bottom of the trunk body 1, adjacent to the hinged end wall 2, and preferably beneath the back rail of the fixed plate member of the hanger track 4, the same affording a convenient and very substantial means of attachment of one end of the curtain to the trunk body. In the present improvement the main curtain 6 extends outward above and beyond the hanger track 4, and then downward to near the other fixed end wall 70 of the trunk body, to which end wall it is adjustably attached by one or more draw-straps and buckles 7. And the arrangement 75 is such, that with the garment supported in place by means of hangers engaging the hanger-tracks 4 as usual, the draw-straps and buckles 7 can be tightened so as to impart the required tautness to the curtain 6 to compress and hold the garments in place within the main trunk body 1, and at the same time cover over and protect the garments from dust, etc.

In the preferred form of the present invention, as shown, the main curtain 6 is 80 formed with side flaps or extensions 8, 90 which are adapted to be tucked in at the sides of the garments to more effectively inclose and protect the same from dust, etc. And such inclosure and protection of the garments is additionally attained by means 95 of a pair of side curtains 9, which are attached at their upper ends to the side walls of the main trunk body 1, preferably beneath the side rails of the fixed plate member of the hanger track 4, and depending 100 therefrom as shown. Said side curtains 9 are adapted to coat with the side flaps or extensions 8 of the main curtain in affording inclosure and protection for the garments.

Having thus fully described my said invention what I claim as new and desire to secure by Letters Patent, is:—

1. In a wardrobe trunk, the combination 110 of a trunk body having an open end, a

hinged wall associated with said open end, a hanger track secured to the interior of the trunk body in spaced and fixed relation to said open end, a flexible curtain attached at its upper end to the trunk body and extending out over the hanger track and depending from the front of the same, and an adjustable draw strap connecting the lower end of the curtain to the trunk body and adapted to tension said curtain, substantially as set forth.

2. In a wardrobe trunk, the combination of a trunk body having an open end, a hinged wall associated with said open end, a hanger track secured to the interior of the trunk body in spaced and fixed relation to said open end, a flexible curtain attached at its upper end to the trunk body and extending out over the hanger track and depending from the front of the same, and an adjustable draw strap connecting the lower end of the curtain to the trunk body and

adapted to tension said curtain, said curtain being provided with side flaps, substantially as set forth.

3. In a wardrobe trunk, a trunk body having a hinged end wall and a hanger track in adjacent relation to said end wall, a main curtain attached at its rear end to the trunk body, said curtain extending out over the hanger track and depending from the front of the same, a draw strap and buckle connecting the free end of the curtain with the main body of the trunk, and a pair of side curtains attached at their upper ends to the side walls of the trunk body adjacent to the hanger track, substantially as set forth.

Signed at Chicago, Illinois, this 3rd day of July, 1913.

WILLIAM NAGLER.
